UNITED STATES PATENT OFFICE

149,348

DESIGN FOR A FILM VIEWER

Felix Gilbert, New York, N. Y., assignor to Eugene Manufacturing Corp., New York, N. Y., a corporation of New York

Application March 11, 1947, Serial No. 137,523

Term of patent 14 years

(Cl. D61—1)

To all whom it may concern:

Be it known that I, Felix Gilbert, a citizen of the United States and a resident of the city, county, and State of New York, have invented a new, original, and ornamental Design for a Film Viewer, of which the following is a specification, reference being had to the accompanying drawings, forming part thereof.

Fig. 1 is a side view of a film viewer showing my new design;

Fig. 2 is a front view thereof;

Fig. 3 is a rear view thereof;

Fig. 4 is an end view thereof, the opposite end being similar to the end shown.

I claim:

The ornamental design for a film viewer, substantially as shown and described.

FELIX GILBERT.
